(57) **CLAIM**

The ornamental design for an auxiliary bumper-mounted rack for recreational vehicles, as shown and described.

DESCRIPTION

FIG. 1 is a perspective view of an auxiliary bumper-mounted rack for recreational vehicles, showing our new design, shown with environmental structure;

FIG. 2 is a front perspective view thereof;

FIG. 3 is a rear perspective view thereof;

FIG. 4 is a bottom perspective view thereof;

FIG. 5 is a front view thereof;

FIG. 6 is a left side view thereof;

FIG. 7 is a right side view thereof;

FIG. 8 is a top plan view thereof;

FIG. 9 is a bottom plan view thereof; and,

FIG. 10 is another front view thereof.

The rack is shown on an enlarged scale in FIGS. 2-8 as compared with FIG. 1 and on a further enlarged scale in FIGS. 9 and 10 as compared with FIGS. 2-8.

The broken line showing of environment is for illustrative purposes only and forms no part of the claimed design.
